UNITED STATES PATENT OFFICE.

MAX W. HENIUS AND JOHN HERROLD, OF NEW YORK, N. Y.; SAID HERROLD
ASSIGNOR TO SAID HENIUS.

METAL-BENDING MACHINE.

SPECIFICATION forming part of Letters Patent No. 643,354, dated February 13, 1900.

Application filed April 10, 1899. Serial No. 712,374. (No model.)

To all whom it may concern:

Be it known that we, MAX W. HENIUS and JOHN HERROLD, citizens of the United States, and residents of New York, in the county of 5 Kings and State of New York, have invented a new and useful Improvement in Metal-Bending Machines, of which the following is a specification.

Our invention relates to an improvement 10 in metal-bending machines; and it consists more particularly in a device for rapidly and accurately feeding the corset-steels to the bending-rolls of the machine, the said steel-feeding device being under the control of the 15 machine.

A practical embodiment of our invention is represented in the accompanying drawings, in which—

Figure 1 is a view in side elevation of the 20 machine. Fig. 2 is a top plan view of the same with a portion of the device for feeding the corset-steels broken away. Fig. 3 is a vertical section from front to rear through the machine in the plane of the line 3 3 of Fig. 2. Fig. 4 is a top plan view of the machine with 25 the rotary table, which carries the corset-steel hoppers and the stationary table, removed. Fig. 5 is a front view of the machine, the upper portions of the hoppers being broken 30 away. Fig. 6 is a rear view of the same. Fig. 7 is a plan view with the top of the frame removed. Fig. 8 is a vertical section from front to rear through the upper portion of the machine, the parts being in the position which 35 they assume when forming a bend in the corset-steel and the steel-feeding device removed. Fig. 9 represents partial front and edge views of one of the steels after it has been bent; and Fig. 10 represents a detail view of a portion 40 of the stationary table, showing the inclined way at its periphery for directing the corset-steels as they are brought successively into position into the steel-receiving slot of the machine.

The framework of the machine comprises a 45 base A, side frames $a a'$, rigidly spaced apart by cross-bars a^2 , and a top a^3 . The top a^3 has a steel-receiving slot or opening a^4 therethrough in position to direct the steels between the bending-rolls.

A pair of bending-rolls B and C are carried

by shafts b and c , mounted to rotate in suitable bearings in the side frames $a a'$, the bearings for the front roll-shaft b being stationary and the bearings for the rear roll-shaft c having a limited sliding movement toward and away from the front of the machine. These rolls B and C are located near the top of the machine beneath the steel-receiving opening a^4 . An auxiliary frame is hinged 55 within the casing on the shaft c , which frame comprises a pair of side plates $D D'$ and a cross-bar d , connecting their lower ends. A bending-roll E is carried by a rotary shaft e , mounted in stationary bearings in the side 60 plates $D D'$ of the auxiliary frame, the said shaft being located a short distance below the shaft c of the rear roll.

A rotary cam-shaft F is mounted in adjustable bearings in the side frames $a a'$, each of 65 the said bearings of the shaft F being capable of adjustment by means of a pair of adjusting-screws $f f'$, leading from the front of the machine into engagement with one side of the bearing and from the back of the machine into engagement with the other side of 70 the bearing.

The shaft F is provided on one end exterior to the side frame with a drive-pulley f^2 , by means of which the shaft may be driven 75 from a source of power. (Not shown.)

The rotary movement of the shaft F is imparted to the front roll-shaft b by a gear-wheel f^3 on the shaft F between the drive-pulley f^2 and the side frame a , intermediate gear-wheels 80 $G G'$, mounted on stub-axes $g g'$, and a gear-wheel b' , carried by the end of the said shaft b . Rotary movement is imparted from the front roll-shaft b to the rear roll-shaft c , whether the rolls are closer to or farther from 85 each other, by a gear-wheel b^2 on the shaft b and a gear-wheel c' on the shaft c , both of which gears are provided with extra long teeth, so as to permit a considerable movement toward and away from each other without being disconnected. Rotary movement 90 is imparted to the lower roll-shaft e by means of a gear-wheel e' on the shaft e in a different plane from the gear-wheels c' and an intermediate wide gear-wheel H, carried by a shaft 95 h , mounted in the side plates $D D'$ of the auxiliary swinging frame.

A swinging movement is imparted to the auxiliary frame by a pair of cams $f^4 f^5$, carried by the shaft F in position to engage the rear edges of the side plates D D'. A spring 5 d' leads from the cross-bar d of the swinging frame to a bracket d^2 , carried by one of the cross-bars a^2 .

The pivot-shaft c of the swinging frame is caused to slide toward and away from the front 10 of the machine at predetermined intervals during the swinging movement of the auxiliary frame to alternately permit the rolls B and C to engage the rear portion of one steel to bend it and to permit the advance portion 15 of the next succeeding steel to pass freely between the said rolls. This movement is accomplished by providing stop-pins I I', projecting inwardly from the side frames $a a'$ in position to engage the front edges of the side 20 plates D D' at the top of the swinging frame, and a cross-bar I^2 , mounted in sliding bearings in the side frames $a a'$, which cross-bar is caused to engage the rear edges of the side plates D D'. This cross-bar is adjusted by 25 screws i , extending from the back of the side frames into engagement with the sliding bearings of the said cross-bar.

By adjusting the bar I^2 the greatest distance between the rolls B and C may be regulated 30 to suit steels of different thicknesses, and by adjusting the bearings of the shaft F the amount of bend to be imparted to the steels may also be regulated.

A stationary table J is mounted on a suitable support j , secured to the top of the machine, upon which table is mounted a rotary 35 table J'. The stationary and rotary tables are preferably of disk shape of about the same diameter.

40 The rotary table J' is provided with an annular series of funnel-shaped hoppers J², having their lower ends provided with corset-steel-discharge openings j' , extended through the rotary table J', so that when the corset-steels are inserted into the funnels their 45 lower ends will rest upon the stationary table J.

The stationary table J is provided with a downwardly-extended way or guide j^2 at its 50 periphery adjacent to the steel-receiving slot a^4 in the top a^3 of the casing for directing the lower ends of the several steels into the said slot a^4 as they are brought successively into position over the same.

55 The means which we employ for imparting a step-by-step rotary movement to the table J' comprises the following parts: A dog K is mounted to slide forwardly and rearwardly on the top a^3 of the frame, the free end k of the said dog being fitted to engage an annular series of abutments—as, for instance, holes j^3 in the rotary table J'. This arm k of the dog is spring-actuated and passes up into engagement with the rotary table J' through a slot j^4 in the stationary table J.

The sliding dog K is operated by a rocking lever L, having one arm engaged with the dog

and its other arm engaged by a cam f^6 , carried by the shaft F. The rocking lever L is held in engagement with the cam f^6 by a reTRACTING-SPRING l , leading from the lower arm of the hopper to one of the cross-bars a^2 of the frame. 70

A spring-actuated arm k' is carried by the top a^3 of the frame with its free end in engagement with the periphery of the rotary table J'. The said table is provided with notches k^2 , corresponding to the hoppers J², arranged to receive the end of the arm k' , so that the said arm may hold the successive 80 hoppers temporarily in their positions over the steel-receiving opening a^4 in the top a^3 , while the arm k of the dog is brought back into position to engage its next succeeding hole or tooth j^3 . 85

An adjustable stop is located at the front of the machine a considerable distance below the bending-rolls. This stop comprises a table M, having downwardly-extended branches $m m'$, which are secured to the side frames $a a'$ by bolts m^3 , which pass through elongated slots m^2 in the said ears. This stop may be adjusted toward and away from the bending-rolls, so as to determine the point on the steel which is inserted within the machine 95 at which the bend shall be started.

An adjustable discharge-plate N is carried by the auxiliary swinging frame, which plate is provided with ears $n n'$, having vertically-elongated slots n^2 , through which pass clamping-bolts n^3 for clamping the discharge-plate in any desired adjustment. This discharge-plate N is fitted to engage the advance or lower end of the steel as the frame is swung forwardly and positively swing the said steel 105 outwardly away from the machine as it is being bent, thus preventing any tendency on the part of the steel to stick in its first position within the machine.

In operation the corset-steels to be bent are 110 dropped into an annular series of hoppers J². As the machine is operated the dog K will be slid back and forth by the rocking of the lever L, thus bringing the steels successively into position to drop into the opening a^4 in 115 the top a^3 at the proper intervals. As each of the steels is dropped from its hopper into the machine the rolls B and C are moved a distance apart sufficient to permit the steel to fall freely until its lower end rests upon the 120 stop M. The auxiliary frame is then swayed forward, thus bringing the two rolls B and C into contact with the opposite faces of the steel and the roll E into engagement with the inner face of the steel to bend it partially 125 around the roll B. At the same time the discharge-plate N will swing forward and positively free the lower end of the steel from the adjustable stop M.

By the use of the plurality of hoppers for 130 feeding the corset-steels into the machine the machine may be operated at a high rate of speed, thus turning out a maximum number of bent steels in a minimum space of time.

It is evident that slight changes might be resorted to in the form and arrangement of the several parts without departing from the spirit and scope of this invention. Hence we 5 do not wish to limit ourselves strictly to the structure herein set forth, but

What we claim is—

1. In a metal-bending machine, a movable device for containing a plurality of strips of 10 metal, bending-rolls arranged to receive the strips between them, means for operating the bending-rolls and means under the control of the bending-roll-operating means for moving the strip-containing device into position to 15 permit successive strips to fall into position to be engaged by the bending-rolls at predetermined intervals, substantially as set forth.
2. In a metal-bending machine, bending-rolls, means for operating them, a movable table 20 having a plurality of hoppers adapted to receive the strips to be bent and means for successively bringing the several hoppers into position to permit their respective strips to fall into position to be engaged by the bending-rolls at predetermined intervals, substantially 25 as set forth.
3. In a metal-bending machine, bending-rolls, means for operating them, a rotary table, an annular series of strip-receiving hoppers carried thereby and means under the 30 control of the bending-roll-operating means for bringing the hoppers successively into position to feed their respective strips to the bending-rolls at predetermined intervals, substantially as set forth.
4. A strip-feeding device for metal-bending machines comprising a stationary table, a rotary table mounted thereon a plurality of strip-receiving hoppers opening through the 35 rotary table for permitting the lower ends of

the strips to rest upon the stationary table and means for imparting a step-by-step movement to the rotary table for bringing the strips successively to a point on the stationary table where they will be permitted to be fed 45 to the strip-bending mechanism, substantially as set forth.

5. In a metal-bending machine, metal-bending rolls, a rotary cam-shaft for operating the rolls, a rotary feed-table having a plurality of 50 hoppers for the strips to be bent and means for imparting a step-by-step movement to the table for feeding the strips successively to the bending-rolls comprising a pawl arranged to engage successive abutments on the movable 55 table, a cam carried by the cam-shaft and a spring-actuated rocking lever having one arm engaged with the pawl and the other arm with the said cam, substantially as set forth.

6. A strip-feeding device for metal-bending 60 machines comprising a stationary table having a downwardly-extended guide, a rotary table mounted on the stationary table, an annular series of strip-receiving hoppers opening through the rotary table for permitting 65 the strips contained in the hoppers to rest upon the stationary table and means for bringing the hoppers successively into position to cause the strips to pass down the guide on the stationary table into position to be fed into 70 the machine, substantially as set forth.

In testimony that we claim the foregoing as our invention we have signed our names, in presence of two witnesses, this 28th day of March, 1899.
